UNITED STATES PATENT OFFICE.

EDGAR O. SELBY, OF COSHOCTON, OHIO.

DESIGN FOR A BRACKET AND PENCIL-HOLDER.

SPECIFICATION forming part of Design No. 28,059, dated December 21, 1897.

Application filed October 11, 1897. Serial No. 654,895. Term of patent 7 years.

To all whom it may concern:

Be it known that I, EDGAR O. SELBY, a citizen of the United States, residing at Coshocton, in the county of Coshocton and State of Ohio, have invented and produced a new and original Design for a Bracket and Pencil-Holder; and I do hereby declare the following to be a full, clear, and exact description of the same, reference being had to the accompanying drawings, forming a part thereof.

My invention relates to a design for a book, package, and collection-envelop holder or bracket, and is shown in the accompanying drawings, in which—

Figure 1 is an isometrical perspective view of the holder; Fig. 2, a rear or inner side view, and Fig. 3 a vertical transverse section, of the same.

As shown in the said drawings, the leading or material features of my design consist of an ornamental body portion or front plate A, formed with the inturned bottom and side

pieces b c, respectively, having the flanges b' c', provided with the apertured ears d e, forming a continuation thereof. At the upper end 25 of the front plate is an outturned flange f, and on the inner side of said plate contiguous to the said side pieces c lugs or projections g. The envelop-holder thus formed in accordance with my design is closed at the front or 30 outer side, bottom, and sides and open at the rear or inner side and top, as shown.

Having thus fully described my invention, what I claim as new, and desire to secure by Letters Patent, is—

The design for a bracket or holder, as herein shown and described.

In testimony whereof I affix my signature in presence of two witnesses.

EDGAR O. SELBY.

Witnesses:

J. C. ADAMS,
E. I. MANNER.
